UNITED STATES PATENT OFFICE

HARRISON H. EATON, OF TOLEDO, OHIO, ASSIGNOR TO THE ELECTRIC AUTO-LITE COMPANY, OF TOLEDO, OHIO, A CORPORATION OF OHIO

MACHINE FOR REMOVING ARMATURE INSULATION

Application filed April 26, 1928. Serial No. 273,086.

This invention relates to a machine for removing material from articles of manufacture and particularly to means for removing the surplus insulating material remaining upon the periphery of an armature after the coils have been inserted therein.

In the manufacture of armatures for generators or other dynamo electric machines and particularly the smaller sizes thereof, it is the practice to insert a continuous strip of insulating paper or other material into the slots of an armature, the paper extending over or covering the exterior portions of the teeth formed by the spaced slots. The coils are then inserted in the slots in the usual manner and the insulation lying upon the armature teeth is subsequently removed by a cutting or shearing operation. These methods of removing the surplus insulation are somewhat unsatisfactory and the principal object of this invention is the provision of improved means for abrasively removing this insulation.

Another object of this invention is the provision of means whereby the insulating material remaining upon the periphery of the armature may be rapidly and easily removed therefrom without danger of damaging the armature core or the coils thereof.

Another object of the invention is the provision of a machine of this character which will remove the surplus insulation from the teeth of the armature in a comparatively short space of time thus materially reducing the manufacturing costs of armatures.

Still another object is the provision of a machine of this character which is simple in its operation, not liable to get out of order and which may be safely operated by inexperienced workmen.

Other objects and advantages will be apparent from the following description, in which reference is had to the accompanying drawings illustrating a preferred embodiment of my invention wherein the similar reference numerals refer to similar parts throughout the several views.

In the drawings:

Figure I is a side elevational view of the machine of my invention.

Figure II is a top plan view of the machine shown in Figure I.

Figure III is a detail longitudinal sectional view of an armature.

Figure IV is a longitudinal sectional view 55 through the machine taken substantially on the line IV—IV of Figure II.

Figure V is a sectional detail view through one of the brushes forming a part of the machine.

Figure VI is an end view of the parts shown in Figure V.

Referring to the drawings in detail, I have shown my invention as used for removing insulation from armatures, but it is to be understood that I contemplate the use of my device wherever the same may be found applicable. The machine comprises a base 1 of shell like construction in order to reduce the weight thereof to a minimum, the base being formed with a shelf like portion 2 having a pair of upwardly projecting members 3 and 4. Journalled in the members 3 and 4 is a pair of substantially parallel shafts 6 and 7 provided with suitable driving pulleys 8 and 9 fixedly secured thereto and arranged transversely out of alignment. The pulleys 8 and 9 are adapted to be driven by means of belts (not shown) to a suitable source of power. The extremities of the shafts 6 and 7 project through the member 4 and are each provided with a rotary brush of identical construction, one of which is shown in detail in Figure V.

The end of each shaft is provided with a reduced portion 11 which snugly receives a bushing 12 adapted to rotate with the shaft by means of a key or pin 13. Mounted upon the bushing 12 is a plurality of sections of brushes 14 fabricated of wire or other suitable braiding material which are suitably held in compact arrangement on the bushing by means of a washer 15 and a nut 16. The complete assembly of the brushes and bushing 12 are fixedly held on the shaft by means of a nut 18. This particular method of mounting the brush sections makes it possible to quickly and easily replace any worn or damaged brushes.

The brushes 14 form, as particularly shown 100

in Figure IV, a support for an armature A, having insulating paper A' or other material on its periphery, the armature being held in engagement with the brushes by means of a roller 20 or drum made of rubber or other suitable material contacting the periphery thereof, and which is rotatably journaled in bearings 22 in an arm 23. One end of the arm 23 is loosely pivoted upon a shaft 28 and is provided with a weight 24, the function of the latter being to hold the roller 20 in frictional engagement with the periphery of the armature A. The arm 23 is also provided with a handle portion 25 by which the operator may elevate the arm and disengage the roller 20 from the armature to remove the same and insert a new one. I have also provided means whereby the arm 23 may be elevated by the operator's foot, which means 20 comprises a lever 30 suitably fulcrumed upon the shaft 28, one arm of the lever being arranged adjacent the arm 23 and having an inwardly turned portion 31 which is adapted to extend beneath the arm, the other end of 25 the lever 30 being connected by means of a rope or cable 32 to a suitable operating treadle (not shown). It will be obvious that a downward pull on the cable 32 will oscillate the lever 30, bringing the portion 31 thereof into engagement with the arm thereby elevating the latter. In order to prevent the arm 23 from swinging into engagement with the revolving brushes 14 when the armature 30 has been removed from the machine, I have provided a suitable stop 27 which is adapted to engage the lever 30 to limit the downward movement of the arm 23 and parts carried thereby. The arm 23 may be swung to an out-of-the-way position shown in dotted lines 40 in Figure IV when the machine is not in use. The roller 20 is adapted to be driven at a comparatively slow speed in order to cause rotation of the armature A while in engagement with the brushes 14, the driving means 45 comprising a sprocket 34, mounted upon shaft 21, carrying the roller 20, and is connected by means of a chain 35 to a sprocket 36 fixedly mounted upon the shaft 28 and adapted to be driven thereby. 50 Shaft 28 is journaled in bearings in the upper extremities of projections 29, forming integral parts of the base 1. Fixedly mounted upon one extremity of the shaft 28 is a miter gear 38 meshing with a similar 55 and smaller miter gear 39 carried upon a shaft 40, the latter being suitably journaled in the members 41 and 42 also forming integral parts of the base 1. Adjacent the bearing 42 is a worm wheel 44 secured to the shaft 60 40, which is adapted to mesh with and be driven by a worm 46 secured to a longitudinally extending shaft 47 journaled for rotation in bearings 48, the outer end of the shaft 47 carrying a pulley 50 which may be connected by a suitable belt (not shown) to a

source of power. Rotation of the shaft 47 operates to drive the shaft 40 through the worm 46 and worm wheel 44, the shaft 40 in turn driving the sprocket 36 through the medium of the gears 38 and 39, thus causing rotation of the roller 20 at a greatly reduced speed as compared with the speed of rotation of the shaft 47. The shafts 6, 7 and 47 are adapted to be driven by separate driving means so that where several machines of this type are arranged in batteries they may all be driven from a common source of power. 70

The extending portions of the shaft B of the armature A are adapted to receive bushings 55 and 56 which, when the armature is 80 in position in the machine, are adapted to project into the U-shaped guides formed upon members 58 and 59 which are secured to supporting blocks 60 and 61, the latter being supported upon and adjustably secured to the shelf like portion 2 of the base 1. The purpose of the bushings 55 and 56 on the armature shaft B and the adjustable supports 60 and 61 are to provide suitable means whereby armatures having shafts of varying 85 diameters and lengths may be accommodated in this machine. The blocks 60 and 61 are provided with vertical bores 65 within which are positioned pins 66, provided with flanged portions intermediate the ends thereof, springs 68 being interposed between the flanges of the pins and the extremities of the bores 65. The purpose of the pins 66 is to automatically disengage the periphery of the armature from the brushes when the arm 23 is swung upwardly. The weight of the armature A, arm 23 and the parts carried thereby is sufficient to compress the springs 68 and permit the periphery of the armature to contact with the brushes when the armature is properly positioned within the guides 58 and 59. 105

The operation of the machine is as follows:

Assuming that the brushes 14 and the roller 20 are rotating as hereinbefore described, an armature is first provided with the bushings 55 and 56 and is then inserted between the guides 58 and 59. The arm 23 is then manipulated to bring the roller 20 into engagement with the periphery of the armature, the weight of the parts compressing the springs 68 and permitting the armature to contact with the rapidly rotating brushes 14. 110

It will be obvious that the rapid rotation of the brushes 14 will abrade or wear away the surplus insulating material overlying the exterior portions of the armature teeth, which material is comminuted or pulverized and passes downwardly through the opening 5 in the base to be subsequently carried away by means (not shown). The armature A is permitted to complete 2 or 3 revolutions or until the excess insulating material has been removed from the periphery thereof. The arm 115

23 is then elevated either by manipulation of the handle 25 or the treadle operating the cable 32, the spring 68 immediately moving the armature upwardly out of engagement with the brushes 14. The armature may then be removed and the cycle of operations performed upon another armature without stopping the machine.

10 The embodiment of my invention herein shown and described is to be regarded as illustrative only, and it is to be understood that the invention is susceptible to variation, modification, and change within the spirit and scope of the subjoined claims.

15 Having described my invention, what I claim and desire to secure by Letters Patent is:

1. In a machine of the character disclosed, in combination, a frame; movable abrading members supported upon said frame; means for yieldingly supporting an armature adjacent said abrading members; a member engageable with the armature for moving the latter into contact with said abrading members and causing rotation of the armature.

2. In a machine of the character disclosed, in combination a frame; a movable support for an armature; a plurality of abrading members carried by said frame; means for holding the armature in engagement with the abrading members comprising a drum of yieldable material; driving means for the drum; means to move the drum away from engagement of the armature.

3. In a machine of the character described, in combination a frame, a revolving brush carried by said frame, resilient means for holding an armature over said brush; a weighted member of resilient material pivotally mounted over said brush adapted to retain the armature in engagement with the brush; and means for rotating said resilient member.

4. In a machine of the character described, in combination a frame, a brush carried by said frame; means for rotating said brush; an arm pivoted upon said frame; a drum of resilient material carried by said arm, means for supporting an armature between said brush and said drum, said drum acting to retain the armature in engagement with said brush; driving means carried by said pivoted arm for rotating said drum to impart rotation to the armature, said driving means adapted to function irrespective of the position of said drum; and means for rendering said drum ineffective to rotate the armature.

In testimony whereof, I affix my signature.
HARRISON H. EATON.
